DESIGN FOR A WRIST WATCH

Marianne Ostier, New York, N. Y.

Application February 26, 1946, Serial No. 126,909

Term of patent 7 years

(Cl. D42—8)

To all whom it may concern:

Be it known that I, Marianne Ostier, a citizen of Albania, residing at 40 Central Park South, New York 19, in the county of New York and State of New York, have invented a new, original, and ornamental Design for a Wrist Watch, of which the following is a specification, reference being had to the accompanying drawing, forming part thereof.

In the drawing:

Fig. 1 is a top view of the wrist watch, showing my new design in closed position;

Fig. 2 is a front view thereof;

Fig. 3 is a side view thereof; and

Fig. 4 is a perspective view of my new wrist watch showing the same in opened position.

I claim:

The ornamental design for a wrist watch, as shown and described.

MARIANNE OSTIER.
